His Attorney

UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

ELECTRIC SWITCH.

1,374,656.

Specification of Letters Patent. Patented Apr. 12, 1921.

Application filed May 5, 1916. Serial No. 95,596.

To all whom it may concern:

Be it known that I, CHARLES H. HILL, a citizen of the United States, residing at Schenectady, in the county of Schenectady, State of New York, have invented certain new and useful Improvements in Electric Switches, of which the following is a specification.

10 My invention relates to electric switches and more particularly to electric switches of the knife blade type.

In electric switches which control motors or other apparatus, it is necessary for the protection of human life that the live parts 15 of the switch be entirely protected in such a way that an operator cannot touch a switch to replace a fuse or the like until the switch has been opened and cannot close the switch while there is danger of touching 20 live parts. Furthermore, it is also very desirable that when the switch has been opened by the operator in order to make some repairs in the machine or similar apparatus which may for instance be operated 25 by a motor controlled by the switch, that some other person cannot close the switch and start the machine while the operator is repairing or adjusting his machine and is for the time being perhaps concealed from 30 view.

It is the object of my invention, therefore, to provide a novel and improved electric switch which embodies these safety first principles while the particular object of 35 my invention is to provide a switch in which the parts thereof cannot be touched until after the switch is opened and the switch cannot be closed while there is a possibility of one touching live parts. Furthermore, it is the object of my invention to 40 provide a switch which can be locked in open position and in which the switch is so arranged that an operator cannot get at the switch mechanism without authorization to 45 do so.

The novel features which I believe to be characteristic of my invention will be defined in the claims appended hereto, the features of construction and mode of operation being understood by reference to the following description taken in connection with the accompanying drawings, in which:—

Figure 1 shows a front elevation partly

in section of a switch embodying the novel 55 features of my invention, Fig. 2 is a sectional end elevation taken along the line 1—1 of Fig. 1 with a portion taken away for the purpose of clearness, Fig. 3 is an end elevation of my novel switch and Fig. 4 60 is a perspective view of a detail of construction.

In Fig. 1, I have shown, by way of example, the novel features of my invention applied to a two pole knife blade switch 65 having a movable switch member comprising the contact blades 1 connected by a bar of insulating material 2 to enable the contacts to be operated simultaneously into and out of engagement with coöperating fixed 70 contacts 3. The switch is mounted in a metal protective casing or box 4 which completely incloses the switch. The movable switch blades 1 and contacts 3 are mounted in the upper part of the casing, the casing 75 being provided with an enlarged portion 5 into which the contact blades are movable upon moving to switch opening position. This portion of the switch casing is closed and protects the live parts of the switch. Below the contact blades 1 and in electrical connection therewith are suitably mounted the usual fuse members 6. This portion of 80 the casing is closed by a hinged or pivotally mounted cover or opening member 7 85 which can be opened to replace a blown or disabled fuse but which provides no way of getting into touch with switch mechanism.

For actuating the switch I provide a 90 bowed rock shaft or yoke member 8 pivotally supported or journaled on opposite ends of the casing 4 carried at one end by a trunnion and at the other end on a shaft 9 extending through the casing and having 95 secured thereto, outside the casing, an operating member or handle 10. The yoke member 8 extends around the outside of the switch blades 1 and has an actuating arm 11 secured to the top thereof provided with 100 a bifurcated or forked end which fits over the insulating rod 2 and moves the contact blades 1 in response to the movement of the yoke member 8 by the handle 10. Mounted upon the shaft 9 just inside the casing 1 is 105 a member 12 movable by the handle 10 and carrying thereon a lug 13 having a curved or convex engaging surface. This lug 13,

carried by the operating member 10, coöperates with a flange or lug 14 carried on a member 15 and movable by the cover 7. Lug 14 has a coöperating curved or concave 5 engaging surface with which the curved surface of lug 13 engages to form an interlocking means or mechanism for the switch.

The operation of the switch structure so far described is as follows: Let us consider the switch as in closed position, as shown in Figs. 1, 2 and 3, the operating member 9, being in the switch closing position as shown in Figs. 1 and 3 with the lug 13 carried by the handle, in the position shown in Figs. 1 and 2. The cover 7 of the protective casing 1 for the switch is shown in closed position, in Fig. 2, with its lug 14 in the position it assumes when the cover 15 is closed. With the switch in closed position, it is essential as a safety feature that the cover cannot be opened and this is accomplished by the relation existing between the lugs 13 and 14 when the handle 9 is in the switch closing position. It will be observed if an attempt is made to open the cover 7, its lug 14 engages lug 13 and prevents the opening because the lug 13 in the switch closing position of the handle 9 is in the 25 path of movement of lug 14, or the lugs 13 and 14 are in cover-locking position or relation. The switch, however, can be opened at will by moving the handle 10 from the "on" position shown in Fig. 3 to the "off" 30 position through which movement the contact blades 1 are carried by the yoke 8 and arm 11 through the enlarged portion 5 of the casing shaped for the purpose. In moving the switch to opening position the handle 35 9 carries its lug 13 out of the path of movement of lug 14. Hence when the switch is open, the cover 7 may be opened, the opening of the cover causing the curved surface of its lug 14 to slide over the now substantially concentric curved surface of lug 13 40 to assume the position shown in Fig. 4, the two coöperating surfaces of lugs 13 and 14 being in interlocking engagement. When the cover is open, the handle 9 cannot be 45 moved to switch closing position because the lugs 13 and 14 are then in switch-locking position or relation as lug 14 carried by the cover 7 is then in locking relation or engagement with lug 13 and it is impossible 50 to move lug 13 and hence the handle 9 to close the switch. With this novel interlocking construction I provide a switch which must be opened before the cover of its protecting casing can be opened thus assuring 55 that the operator cannot get at the switch while the parts are alive and at the same time the switch cannot be closed to render its parts alive until the cover has been closed to protect the same. The casing is also 60

constructed so that only the fuses are available to the operator when he opens the cover, the switch mechanism being in the upper part of the casing which cannot be reached. An operator can therefore replace a blown fuse in his switch and in doing so is always 65 70 protected from live parts of the switch.

In practice such a switch as described is often used to control the circuit of a motor operating a machine of some sort. Suppose the operator opens the switch to make 75 some repairs or adjustments on this machine and then gets under the machine or otherwise conceals himself from view in his work on the machine. If the switch was accidentally closed while he was in such a position, it would result in his injury. To safeguard the operator under these conditions, I provide an offset locking portion or member 16 carried by and movable with the cover 7 being, preferably substantially 80 U-shaped and provided with two holes 17 and 18, as best shown in Fig. 1. Coöperating with this member 16 is an offset member 19 carried on or secured to the switch casing 1 and provided with an opening 85 90 adapted to register with opening 17. The handle or operating member 9 carries also an offset portion or member 20 provided with a hole 21 which is adapted to register with opening or hole 18 on member 16. 95

In the position shown in Fig. 3, the switch is closed and the cover is closed. In this position hole 17 of member 16 and the opening in member 19 are in alinement and are so provided that a lock of ordinary construction can be slipped through the registering holes and locked. This prevents the cover 7 of the switch casing being opened by any unauthorized person but does not prevent the operating member from being operated to open or close the switch. The key to this lock is carried by the electrician who is the only one authorized to open the switch casing cover to replace fuses or do other 100 105 110 repairs.

When the switch is open, the operating member is in switch opening or "off" position and in this position, the hole 21 in the offset member 20 carried by the operating arm registers with or is in alinement with 115 the hole or opening 18 in the offset member 16. The operator is provided with a lock which he can then insert through the registering holes 21 and 18 and lock the switch in the open position. He is then free to repair the machine or adjust it without any danger of any unauthorized person closing the switch and subjecting him to possible injury. At the same time the insertion of the operator's lock in the registering holes 120 125 125 21 and 18 prevents the electrician from opening the cover 7 even after he removes his lock from the members 16 and 19 due to

the fact that the operator's lock is holding the cover 7 and before the cover can be opened the operator must remove his lock.

My invention may be embodied in many other forms than that shown and described and I, therefore, do not wish to be restricted to the precise construction disclosed, but intend to cover by the appended claims all changes and modifications within the spirit 10 and scope of my invention.

What I claim as new and desire to secure by Letters Patent of the United States, is:—

1. In an apparatus of the class described, a switch, a casing inclosing said switch, a lever adapted to be operated to open and close said switch, a lug mounted to move with said lever and provided with two opposed convexly curved faces, a cover hinged to said casing, and a curved flange on said 20 cover arranged so that one end thereof abuts one of the faces of said lug when the switch is closed to prevent opening said cover, said lug being mounted to move out of abutting engagement when the switch is opened to

permit the movement of said flange over the 25 other face of said lug whereby the switch cannot be closed when the cover is open.

2. In an apparatus of the class described, a switch, a casing inclosing said switch, a lever adapted to be operated to open and 30 close said switch, a cover hinged to said casing, a curved flange on said cover, a lug mounted to move with said lever, characterized by the fact that said lug is provided with two opposed curved faces, one of said 35 faces being in abutting engagement with one end of said flange when the switch is closed to prevent opening the cover and the other face being of substantially the same curvature as said flange and concentric therewith 40 when the switch is fully open whereby the flange is permitted to move over said face upon the opening of said cover so that the switch is locked against closing while the 45 cover is open.

In witness whereof I have hereunto set my hand this 4th day of May, 1916.

CHARLES H. HILL.
